UNITED STATES PATENT OFFICE.

ROY E. GEARHART AND FRED STEFFENS, OF ST. JOSEPH, MISSOURI.

MONEY-CHANGER.

1,369,801.

Specification of Letters Patent. Patented Mar. 1, 1921.

Application filed June 9, 1919. Serial No. 302,849.

To all whom it may concern:

Be it known that we, ROY E. GEARHART and FRED STEFFENS, citizens of the United States, residing at St. Joseph, in the county 5 of Buchanan and State of Missouri, have invented certain new and useful Improvements in Money-Changers, of which the following is a specification.

This invention relates to coin changers of 10 that class usually strapped to the body, and comprising a series of tubes, pivoted rings underlying the tubes, and levers for swinging the rings laterally to deliver the respective coins from the bottoms of the tubes. 15 Our object is to produce a device of this character whereby through the operation of a predetermined lever, change for the desired amount may be made, whether the amount shall be change for a nickel, a dime, 20 a quarter or a half dollar.

With this general object in view the invention consists in certain novel and useful features of construction and organization of parts as hereinafter described and 25 claimed; and in order that it may be fully understood, reference is to be had to the accompanying drawings, in which:

Figure 1, is a front view of a coin changer embodying the invention.

30 Fig. 2 is a rear view of the device.

Fig. 3, is a horizontal section of the same with a fragment of the top plate in position.

Fig. 4, is a section on the line IV—IV of 35 Fig. 1.

Fig. 5, is a section on the line V—V of Fig. 1.

Fig. 6, is a detail perspective view of a 40 pair of rocker bars to more clearly show the construction thereof and their relation to each other.

In the said drawings, 1 indicates a base plate provided at its rear margin with an upwardly projecting wall 2 and at the upper edge of said wall with a forwardly projecting 45 flange 3, to which are suitably secured over the base plate, vertical coin tubes 5, 6, 7, 8 and 9, the tubes 5 and 7 being adapted for holding nickels, tube 6 for holding pennies, tube 8 for holding dimes and tube 9 50 for holding quarters, and said tubes are provided with the customary sight openings, and covering and secured to the upper ends of the tubes is a top plate 10 formed with coin receiving slots 11 over the respective 55 tubes.

edge with five notches 1^a corresponding in diameter but offset with respect to the adjacent tubes, and interposed between said base plate and the respective tubes and overlapping said notches are rings 5^a, 6^a, 7^a, 8^a and 9^a, the same respectively being of depth to hold one nickel, five pennies, two nickels one dime and one quarter. Each ring is provided with an offset lug 13 pivoted to the 65 base plate at such point that when the respective rings are swung forward their full distance they register accurately with the corresponding notch of the base plate so that the coin or coins inclosed by a ring 70 shall drop through said notch. Each lug 13 is intergeared at 14 with a mutilated gear 15 journaled on the base plate, and the gears 15 engage the lower ends of crank arms 16 of rock lever 17 mounted on pivots 18 carried by ears 19 projecting from the back wall or wall 2 of the base plate, and to hold said rings yieldingly in register with their respective coin tubes, coiled springs 20 are mounted on the pivots 18 and bear at their 80 opposite ends against the back or wall 2 of the base plate and against the respective crank arms 16. The operation, that is the depression of any one of the rock levers 17 effects the swinging movement of the connected ring as hereinbefore referred to and 85 effects the discharge of the coin or coins within said ring and at the same time upholds and retains within the tube all overlying coins until the ring has been returned 90 to its normal position when another coin or coins drop into it and upon the notched base plate. The device is provided with the customary hanger hooks 21 and as thus far described is of common and well-known construction, outside of the fact that this 95 device shows two tubes and equipment for handling nickels.

To equip the device with attachments whereby the full change for any coin up to 100 the capacity of the machine may be delivered by the operation of one lever, we have provided the following mechanism: 22 are bearing lugs projecting upwardly from the flange 3 of the frame constituted by the base plate and back wall, and extending through said lugs is a pivot rod 23. Mounted pivotally on the pivot rod and located behind tube 5, is an inverted U-shaped rock lever 24 having finger piece 25 projecting forwardly between tubes 5 and 6, and said rock 105

110

ing upon the underlying rock levers 17, so that by the depression of finger pieces 25, rings 5^a and 6^a can be simultaneously operated and thus respectively deliver a nickel 5 and five pennies.

A rock lever 28 is also pivoted on the rod 23, and is provided with a single operating finger piece 29 and with forwardly and downwardly projecting arms 30, 31 and 10 32, the arm 30 lying back of and below arm 27 and like the latter terminating upon the underlying rock lever 17. The arms 31 and 32 bear the same relation to the underlying rock lever 17 as the arm 30. It will thus 15 be seen that depression of finger piece 29 effects operation of the rings 6^a, 7^a and 8^a and hence will effect the simultaneous discharge of five pennies from tube 6, two nickels from tube 7 and one dime from tube 8, 20 the amount totaling change for a quarter.

To effect the simultaneous operation of the rings 6^a, 7^a, 8^a and 9^a and thus deliver change for a half dollar, a rock lever 33 is mounted on the rod 23 below the rock lever 25 28, and is provided with an arm 34 to engage the upper side of the underlying rock lever 17. The said rock lever 33 is also provided at its rear edge with an upwardly projecting wall 35 standing slightly rearward of rock lever 28, and projecting from said rear wall 35 is a finger piece 36, the depression of which through arm 34 effects the forward swing of ring 9^a, and through the back wall 35, the rocking of the rock lever 28, and hence the operation of rings 6^a, 7^a, 8^a and 9^a the simultaneous operation of the four rings thus effecting the discharge of five pennies, two nickels, one dime and one quarter at the same time.

40 Underlying the tubes is a hopper so shaped that the coins discharged will readily slide or roll to the exit opening 38 under which the conductor or other operator will place his hand for their reception.

45 A device of the character described for enabling a conductor or the like to give change up to any predetermined amount by a single operation of one lever is desirable not only because it enables change to be 50 made accurately and therefore avoids chances for dispute, but it is also desirable because it greatly facilitates the loading of street cars as the incoming passengers can be handled with much greater facility and 55 thus avoid the holding of the car for considerable periods of time, this quick loading

being of great importance to the successful handling of street cars and more especially of what are known as one man cars now being experimented with in a number of 60 cities with the idea of handling the traffic expeditiously.

From the above description it will be apparent that the invention is susceptible of modification in minor particulars without 65 departing from the principle of construction involved or sacrificing any of the advantages of the appended claims.

We claim:

1. A money changer comprising a base 70 plate having five marginal recesses, coin tubes overlying and spaced from the base plate and overlapping said recesses, pivoted rings between the base plate and the respective tubes, yielding means holding the rings 75 axially aligned with the respective tubes, individual levers geared to the rings to swing the same edgewise to sweep coins from the bottoms of the tubes to a position whence they shall fall through said recesses, a rock-lever having a pair of arms engaging a pair 80 of said individual levers and a single operating finger; a second rock-lever having an arm for engaging one of the individual levers engaged by an arm of the first-named 85 rock-lever and having two other arms engaging two of the individual rock-levers and also having a single finger-piece, and a third rock-lever having an arm for engaging the fifth individual rock-lever, a finger-piece, and a part for imparting rocking 90 movement to the said second rock-lever.

2. In a money changer, a plurality of coin-holding tubes, means for extracting coins from the lower end of said tubes, a series 95 of individual levers to operate said means respectively, a rock-lever having a pair of downwardly curved arms for operating two of the individual levers simultaneously, a second rock-lever having a downwardly-curved arm for engaging one of the said 100 individual levers engaged by one of the arms of the first-named rock-lever, and two other arms engaging two of the other individual rock-levers, and a third rock-lever having 105 an arm for engaging the fifth individual rock-lever and a part for imparting rocking movement to the said second rock-lever.

In testimony whereof we affix our signatures.

ROY E. GEARHART
FRED STEFFENS.
